UNITED STATES PATENT OFFICE.

JAMES T. ANDREW, OF MONTGOMERY, ALABAMA.

SAFETY APPLIANCE FOR RAILROAD-CARS.

No. 844,228.

Specification of Letters Patent.

Patented Feb. 12, 1907.

Application filed May 18, 1906. Serial No. 317,578.

To all whom it may concern:

Be it known that I, JAMES T. ANDREW, a citizen of the United States, residing at Montgomery, in the county of Montgomery and State of Alabama, have invented certain new and useful Improvements in Safety Appliances for Railroad-Cars; and I do hereby declare the following to be a full, clear, and exact description of the invention, such as will enable others skilled in the art to which it appertains to make and use the same.

My invention relates to improvements in safety appliances for railroad-cars; and the object of my invention is to provide means whereby derailment of a train, with its accompanying destructive effects, shall be rendered practically impossible.

My invention is applicable not only to railroad-cars, but also to electric cars of all descriptions and to locomotives.

Other objects will appear in the description.

With this object in view my invention consists in the construction and combinations of parts, as hereinafter described and claimed.

In the accompanying drawings, Figure 1 is a side elevation of the ordinary passenger-truck, showing my invention applied thereto. Fig. 2 is an end view of the same. Fig. 3 is an enlarged view, partly in section, showing my invention in actual use lifting one of the car-wheels. Fig. 4 is a cross-section thereof on the line 4-4 of Fig. 3. Fig. 5 is a perspective view of one form of my improved shoe. Fig. 6 is a side view showing how the movement of the shoes automatically sets the air-brake. Fig. 7 is a top plan view of the same. Fig. 8 is a perspective view of the inner supporting-brace. Fig. 9 is a perspective view of the supporting-bracket introduced into the journal-box. Fig. 10 is a side elevation of a modified form of my invention. Fig. 11 is a longitudinal section of said modified form, and Fig. 12 is a cross-section of the same.

In the drawings, *a* represents an ordinary passenger-truck, having the usual side beams, journal-boxes, springs, &c., which need no further description. Underneath each journal-box two movable shoes, such as *b* and *c*, are located, there being therefore eight of

these shoes to every truck. These shoes may be easily applied to the existing trucks without any alteration and with very slight expense. Said shoes are shown in perspective in Fig. 5, and each of them consists of a cam-shaped portion *d*, provided with a rounded lower edge *e* and rounded ends, such as *f*. It is also provided with a flange *g*, located on the same side of the car as the corresponding flange on the car-wheel. The inner shoe, such as *c*, has a flange, such as *h*, extending the complete length of the shoe and of practically the same depth throughout, while the flange on the outer shoe practically disappears at the center and enlarges near the ends, as shown in Fig. 3. The reason for having the flange on the outer shoe constructed in this way is to allow in case of spread track the outer shoe to fall upon the rail when the wheel runs off and to support the car, the shoe being then thrown up into the position shown in Fig. 3, thus bringing the wheel back into position on the rail after the spread portion of the track has passed.

The shoe is constructed, as shown in Fig. 5, of two castings, the main portion *d* having an upwardly-projecting ear *i*, a depression *j* for the reception of the pivot-pin, and holes *m* for the reception of the springs hereinafter referred to. The other piece of the shoe consists of an upwardly-extending perforated ear *o* and sidewise-extending portions *p*, which fit into corresponding depressions cut in the top of the shoe. The detachable piece *s* is held in place by means of bolts *r*. In Fig. 5 the detachable piece is shown on the inside of the shoe; but it could be placed on the outside of the shoe, if preferred. The shoes are held in position by means of a supplemental beam *s*. (Shown in Figs. 1 and 3.) This is attached by bolts *t* to the regular equalizing-frame of the truck and to the outside beams *u* and also by bolts through the pedestals *v* and the frame of the truck. From these beams, if desired to strengthen the construction, a collar may extend from beams *s* completely around the journal-boxes. These beams *s* are provided with a downward projection *w* for the reception of the pivot-pin *x*, which runs through the ears *i* and *o* on the shoe. The pin *x* is welded to the beam *i*,

thereby forming an integral part thereof. In each of the holes *m* is fastened, by means of a pin, a tension-spring *y*, which is attached at its upper end to a yoke *1* on the beam *s*. Under ordinary conditions these springs will hold the shoe in the position shown in Fig. 1; but in case of accident, as shown in Fig. 3, when the shoe strikes the rail the momentum of the car will rock the shoe back into the position shown in Fig. 3, which will have the effect of automatically raising the car-wheel and truck out of harm's way and at the same time will set the air-brakes automatically along the entire train by the means shown in Figs. 6 and 7. Each truck carries eight of these shoes—four shoes outside of each of the truck-wheels and four inside. The inside shoes are connected so that when moved they will automatically open a valve in the train-pipe of the air-brake system and set the brake.

Referring to Figs. 6 and 7, 2 represents the train-pipe of the air-brake system, which is provided with a valve which is controlled by a lever having two arms 3 and 4. To the arm 4 are attached cables 5 and 6, running over guide-pulleys 7, one of these cables running to each of the inside shoes of the truck. Similarly, to the arm 3 are attached cables 8 and 9, running over guide-pulleys 10 and 11, and connected to the inside shoes near their other end. The construction on either side of the truck is the same as is shown in Fig. 7. It is obvious that the movement of one of the shoes from the position shown in Fig. 1 to that shown in Fig. 3 will open the valve and allow the air to escape from the train-pipe, thereby automatically setting the brakes throughout the train, and this result will be effected, no matter which way the shoes are moved upon their pivot-pins, by means of the connections shown in Fig. 6.

The manner of mounting the inner shoes will next be described.

To the main frame of the truck are attached depending beams 11 and a depending center beam 12, to which beams is attached an approximately triangular brace 13. (Shown in detail in Fig. 8.) This construction is the same at both ends of the truck and is used for the purpose of lifting the car out of harm's way, as shown by the connections with the shoes *c*. Under ordinary circumstances the axles 14 of the wheels run freely in the beams 11.

15 represents a brace which is adapted to be placed in the journal-box, as shown in Fig. 3. Under ordinary circumstances the upper part of this brace, which is mounted as shown at 16, does not come in contact with the journal of the axle; but when the wheel is derailed then the shoe lifts the whole structure, carrying the brace 15 into contact with the journal, thereby overcoming the lateral

play in the journal-box and lifting the journal and wheel out of harm's way.

Referring to Figs. 10 and 11, a modified form of my lifting-shoe is shown. 17 represents a beam similar to the beam *s*. This is provided with depending flanges or guide-plates 18 and 19. (Shown in Figs. 10 and 12.) The beam 17 is provided with projecting portions 20 and 21, against which the rounded ends of the shoe 22 are adapted to strike. It is also provided with a journal-socket 23, within which socket fits a toothed or smooth pinion 24, mounted on a pin 25, which is supported in the depending guide-plates 18 and 19. If desired, the lower face of the outer shoe of each pair may be made broader than the corresponding face of the inner shoe; but between the flanges it must conform to the gage of the road. 22 represents the shoe, provided with the tension-springs 26, similar to those already described, and also provided with a flange 27, similar to flange *g*, (shown in Fig. 5,) and is also provided on each side with a curved slot 28, and in these slots fit curved projections, such as 29, on the guide-plates 18 and 19. These curved projections 29 serve to support and guide the shoe or allow it to be freely rocked back and forth. In Fig. 11 the upper part of the shoe is shown as provided with gear-teeth 30, and the pinion 24 is shown as provided with gear-teeth 31, meshing with the gear-teeth 30. The construction would be perfectly operative, however, if the contact-surfaces of the parts 22 and 24 was smooth instead of being toothed.

The operation is as follows: Supposing that the train leaves the track for any reason—as, for example, a broken flange on one of the car-wheels, especially while traveling around a curve either to the right or to the left, or on account of a spread track, or on account of a broken rail, or of a misplaced switch—in this case some part of the truck will drop slightly and one or more of the eight shoes will strike the rail. The result will be that said shoes will be thrown back, as shown in Fig. 3, against the tension of one of the springs *y*, thus lifting the truck out of harm's way and at the same time automatically setting the brakes. The shoes will then slide along the rails, lifting the wheels over cross-rails, guard-rails, and through frogs and preventing them from falling upon the cross-ties. The result is that the train is automatically stopped very quickly, and at the same time the wheels are lifted out of harm's way. Ordinarily the shoes are kept suspended about two inches above the rail, as shown in Fig. 1. It should be noted that the distance between the inner flange of the outer wheel on one side and the inner flange of the inner wheel on the other side, the latter being the inside shoe, is exactly the same gage as that of

the track itself, so that in case of derailment the shoes which catch the truck will be exactly the same gage as the track and will pass between the rails at frogs and switches. For example, if the train should be derailed and moved to the right from the position shown in Fig. 2 the shoe *c* would engage one of the rails and the opposite shoe *b* would engage the other of the rails and immediately lift the wheels above the rails and apply the brakes automatically, as previously described, and the shoes *b* and *c* would slide along the rails, assisting the train to come to a stop.

While I have thus described my invention, I wish it to be particularly understood that I do not limit myself to the exact details shown and described, as these might be varied widely without departing from the spirit of my invention, the essence of which is that in case of derailment of any part of the train the derailed portion is lifted out of harm's way, and the train is automatically stopped before any appreciable harm can be done either to the track or to the rolling-stock.

Having thus described my invention, what I claim as new, and desire to secure by Letters Patent, is—

1. In a safety appliance for cars and locomotives, the combination of trucks, pivoted shoes freely suspended from said trucks, and connections whereby in case of accident said shoes are brought in contact with the rails to automatically lift the trucks and automatically set the air-brakes, substantially as described.

2. In a safety appliance for cars and locomotives, the combination of trucks and means carried thereby for automatically lifting said trucks and setting the brakes in case of accident, substantially as described.

3. In a safety appliance for cars and locomotives, the combination of trucks, pivoted shoes carried by said trucks, tension-springs for said shoes whereby said shoes are normally kept out of contact with the rails, said shoes being provided with curved lower faces, and with flanges corresponding to the gage of the rails whereby in case of accident said shoes are brought in contact with said rails thereby causing them to be tilted and automatically lifting said truck, substantially as described.

4. In a safety appliance for cars and locomotives, the combination of a truck, shoes pivoted thereon, tension-springs between said truck and said shoes, said shoes being provided with flanges corresponding to the gage of the railroad whereby in case of accident said shoes drop upon the rails and automatically lift the truck out of harm's way above the level of the track and connections whereby the rocking of said shoes upon their

pivots automatically sets the air-brakes, substantially as described.

5. In a safety appliance for cars and locomotives, the combination of a truck and a plurality of paired shoes, one pair for each wheel, the outer and inner shoes for each corresponding pair being of the same gage as the railroad, said shoes being pivotally supported by said truck, and being provided with flanges and also with tension-springs to normally hold them in level position while allowing them to be tilted in case of accident, thereby raising the wheels above the level of the rails, substantially as described.

6. In a safety appliance for cars and locomotives, the combination with truck-frame, supports thereon provided with journals, paired shoes, one pair for each wheel supported by said journals, said shoes each having a rounded lower surface and rounded ends and provided with tension-springs, said shoes being adapted to contact with the surfaces in case of accident in place of the wheel, and if tilted to automatically lift the wheels above the level whereby said tilting movement sets the brakes, substantially as described.

7. In a safety appliance for cars and locomotives, the combination with a truck, of a pair of shoes for each wheel pivotally supported on said truck, tension-springs normally holding said shoes level, each of said shoes being provided with a flange located in a position thereon corresponding to the flange of the adjacent wheel whereby in case of accident said shoes will drop upon said rails and automatically lift the truck above the level of said rails, and a braced frame supporting the inner members of two of the oppositely-arranged pairs of shoes, substantially as described.

8. In a safety appliance for cars and locomotives, a supporting-bracket, said bracket having an enlarged base and curved upper surface adapted to be placed in the journal-box, but normally out of contact with said journal, substantially as described.

9. In a safety appliance for cars and locomotives, the combination with a truck-frame, of shoes pivotally supported thereby and a lifting-bracket adapted to be inserted in the journal-boxes, whereby when the shoe is tilted thereby lifting the truck-frame, the pressure is transmitted to the journal of the axle, substantially as described.

10. In a safety appliance for cars and locomotives, the combination with the truck-frame, of a pair of shoes for each wheel pivotally supported on said frame, each shoe being provided with a flange on its lower face and a braced gage-frame supporting the inner shoes of two corresponding pairs thereby being a brace and guide to keep the whole

structure in conformity with the gage of the road, substantially as described.

11. In a safety appliance for cars and locomotives, the combination of a supporting-beam, depending guide-plates provided with curved flanges connected to said beam, a journal-box, and a movable shoe provided with curved guide-grooves engaging with the

projections on the guide-plates, substantially as described.

In testimony whereof I affix my signature in presence of two witnesses.

JAMES T. ANDREW.
